UNITED STATES PATENT OFFICE.

GUSTAV KINNER, OF PATERSON, NEW JERSEY.

DESIGN FOR A SHOE-TIP.

SPECIFICATION forming part of Design No. 24,667, dated September 10, 1895.

Application filed May 4, 1895. Serial No. 548,167. Term of patent 3½ years.

To all whom it may concern:

Be it known that I, GUSTAV KINNER, a citizen of the United States, residing at Paterson, in the county of Passaic, in the State of New Jersey, have invented and produced a new and original Design for Shoe-Tips, of which the following is a specification, reference being had to the accompanying drawings, which form a part thereof.

10 The drawings represent the design, Figure 1 showing the tip and Fig. 2 a shoe with the tip thereon.

The leading feature of the design consists in the broken or corrugated outline of the sides which converge to form a point. Star-like ornamentations are also distributed over the surface of the tip.

What I claim is—

The design for a shoe tip substantially as herein shown and described.

GUSTAV KINNER.
